(57) **CLAIM**

The ornamental design for a veta power converter, as shown and described.

DESCRIPTION

FIG. 1 is a perspective view of the veta power converter of the present invention;

FIG. 2 is a right side view of the veta power converter of the present invention;

FIG. 3 is a left side view of the veta power converter of the present invention;

FIG. 4 is a front view of the veta power converter of the present invention;

FIG. 5 is a back view of the veta power converter of the present invention;

FIG. 6 is a top view of the veta power converter of the present invention;

FIG. 7 is a perspective view of the veta power converter of the present invention providing a space to insert a bead to provide extra filtering to reduce signal ripple and noise;

FIG. 8 is a right side view of the veta power converter of the present invention providing a space to insert a bead to provide extra filtering to reduce signal ripple and noise; and, FIG. 9 is a bottom view of the veta power converter of the present invention.

The broken line showing of the environment is for illustrative purpose only and forms no part of the claimed design.
